UNITED STATES PATENT OFFICE.

FRANK W. SKINNER, OF TOMPKINSVILLE, NEW YORK.

INTERLOCKING SHEETING.

1,068,178.

Specification of Letters Patent. Patented July 22, 1913.

Application filed October 14, 1912. Serial No. 725,680.

To all whom it may concern:

Be it known that I, FRANK W. SKINNER, a citizen of the United States, residing at No. 41 Sherman avenue, Tompkinsville, New York, have invented a new and useful form of steel or iron interlocking sheeting for use in coffer-dams and caissons, to inclose excavations, to exclude or retain earth and water, and to act in general as sheet-piling.

Heretofore steel or iron sheeting or sheet piles have been largely used for such purposes and have generally been comparatively heavy rolled shapes, or have been fabricated from plates or shapes riveted together, both types often having a large part of the metal not efficiently located in the cross section, and thus being costly to the point of being prohibitive for many places where light, cheap and efficient sheet piles are desirable. Most of the few types of sheet piles now on the market in the United States, are made in only two or three widths and have wide clearances in their joints that prevent them from being watertight unless great pains are taken to calk them or they become silted up.

My invention gives a pile unit of any width, thickness and weight required, that is fabricated simply, quickly, and cheaply from a single sheet by merely bending it without riveting, and that is lighter and easier to handle than most other types, that is especially adapted to short lengths and easy driving where tight continuous structures are the principal requirement, and that can be fabricated much more cheaply than any other section not completed in the rolls. When made of heavy sheet metal or plates, these piles may be driven directly by hammers in the usual manner. If their thickness is very small so that they can not endure heavy hammering directly on the pile tops, they may be driven by driving bars described in my Patent 842,120 and are especially suitable in many places where it is customary to excavate in advance on one side of the pile and drive it down with earth friction on the other side only.

My invention consists essentially in parallel double interlocking flanges formed integral with the web or body of the pile on its longitudinal edges by bending, pressing, rolling or other suitable means.

The drawing is a cross section of a sheet pile unit having a channel-shape cross section with double flanges integral with the web, with their short legs both toward the center of the web and the web extending across the spaces between the legs of each flange.

In the drawing 1 is the web, and 2 and 3, are respectively the long and short legs of the double flanges. The dotted lines represent part of the outlines of duplicate pile sections in reversed position with one double flange of each engaging and interlocking with a double flange of the unit shown by full lines. This figure shows the simplest type of cross section, namely a straight web with double flanges substantially at right angles with it, and having substantially parallel legs. My invention covers any cross section having two double flanges intersecting the web with the short legs of the flanges between the long legs and the center of the web. The web may be straight, bent, curved, plain or ribbed, or of any suitable cross section, and the flanges may make any angle with the web and the cross section of the double flanges may have any suitable shape, and may be alike or different in both flanges, and the two legs of either flange may be parallel or convergent or divergent, and may be curved or straight.

I claim as my invention,

1. A sheet pile unit symmetrical about its longitudinal center line, and having two longitudinal flanges integral with, and approximately at right angles to the web, each flange bent nearly double on a longitudinal line near its center and with the short legs on the insides of the flanges, toward the center line of the unit.

2. A sheet pile unit with two double longitudinal flanges each of which has one long leg integral with the web and making an angle with it, and a short leg integral with the long leg and on the side of the long leg toward the center of the pile and toward the other flange.

Signed at New York city this eleventh day of October, 1912.

FRANK W. SKINNER.
